UNITED STATES PATENT OFFICE.

FRANÇOIS TRÉCHOT, OF PARIS, FRANCE.

TRACTION WHEEL WITH MOVABLE BLADES.

Application filed March 30, 1921. Serial No. 457,114.

To all whom it may concern:

Be it known that I, FRANÇOIS TRÉCHOT, a citizen of the French Republic, and a resident of 152, Avenue Victor Hugo, Paris, France, have invented new and useful Improvements in Traction Wheels with Movable Blades, of which the following is a specification.

The present invention relates to a wheel 10 with movable blades for tractors, sleighs and generally all self-propelled vehicles.

This wheel is of the kind comprising a cylinder or drum revolving around an axis lying transversely of the direction of motion, the said drum being provided with slots through which can pass paddles or blades mounted so as to be revolvable around an axis, which is eccentric in relation to that of the drum, so that the blades, carried 20 round by the rotation of the drum, project in turn through the slots in the said drum and thus effect the propulsion.

The main characteristic feature of the present invention consists in that the drive 25 of the movable blades is effected by the drum itself, which is rotated through chains, bevel gear, worm gear or in any suitable manner, while the shaft, carrying the movable blades, remains stationary.

30 This arrangement may also be used in combination with an arrangement which allows of varying the setting position of the crank shaft with respect to the frame of the vehicle so as to be able to vary at will 35 the portion of the cylinder or drum in which the movable blades project, as is already the case in wheels of the same kind.

The annexed drawings show by way of examples propeller wheels according to the 40 present invention.

Fig. 1 is an elevation, partly in axial section, of a wheel for a tractor.

Fig. 2 is a transverse section, taken on line 4-4 of Fig. 1.

45 Fig. 3 is a somewhat diagrammatic elevation of the tractor, equipped with the wheel of Figs. 1 and 2.

Fig. 4 is a corresponding plan view thereof.

50 In the case of wheels designed for use on self-propelling road vehicles, tractors or the like, there may be adopted the form of construction shown in Figs. 1, 2, 3 and 4.

55 The wheel comprises two symmetrically arranged parts, each comprising a driving drum *a* secured to two lateral crowns *b*,

which are journaled, through roller bearings *c* or the like, on webs *d* of the frame. Within those webs *d* is mounted the crank-shaft *d*¹, on the crank pin of which are journaled collars or spiders *e*, provided with forks *f*, in which are pivotally mounted the carriers *g*¹ of blades *g*, adapted to pass through slots *h* in the periphery of the drum *a*. Members *j* are provided for guiding and 60 cleaning the blades (Fig. 2). The blades, the working edges of which are of curvilinear shape, are inclined to the axis of rotation of the drum and are symmetrically located on both drums (see Fig. 4), so as to 65 gradually enter within the ground and to balance the lateral strains.

The wheel, formed by the two drums and cooperating blades and other parts, is given its movement of rotation through a central 75 worm gearing *m* *m*¹, actuated by means of the shaft *m*², operated by the engine (not shown), through the toothed wheels *m*³ *m*⁴. A housing *n*, engaged into slots *n*¹ of the crowns *b*, protects the worm wheel *m*¹ from 80 the mud or dirt.

The setting position of the crank-shaft *d*¹ in relation to the webs *d* may be varied by means of a worm gearing *l* *l*¹, actuated through a rod and hand wheel *l*²; this operation, by rotating the crank-shaft, allows of 85 changing the portion of the drum through which the blades project.

What I claim is:

1. A wheel with movable blades for tractors, sleighs and generally self-propelled vehicles comprising a drum adapted to rotate around an axis lying at right angles to the direction of motion of the vehicle, means for rotating said drum, slots provided in the 95 periphery of said drum, a transverse normally stationary crank shaft, a collar loosely mounted on said crank shaft and independent of the drum, blades pivotally connected to said collar within the drum and 100 adapted to pass through the slots of the drum, said blades being driven by the rotation of the drum.

2. A wheel with movable blades for tractors, sleighs and generally self-propelled vehicles, comprising webs secured to the vehicle frame, a drum adapted to rotate around an axis lying at right angles to the direction of motion of the vehicle, bearings between the said drum and the webs, means 105 for rotating said drum, slots provided in the periphery of said drum, a transverse nor-

mally stationary crank shaft, loosely carried by the webs, a collar loosely mounted on said crank shaft and independent of the drum, blades pivotally connected to said collar within the drum and adapted to pass through the slots of the drum, said blades being driven by the rotation of the drum.

3. A wheel with movable blades comprising two symmetrically arranged drums, 10 adapted to rotate around an axis lying at right angles to the direction of travel of the vehicle, means for simultaneously rotating both drums, slots provided in the periphery of said drums, a transverse stationary crank shaft, collars loosely mounted on said crank shaft in each drum and independent of the said drum, sets of blades pivotally connected to said collars within each of said drums and adapted to pass through 15 the peripheral slots thereof, said blades being driven by the rotation of the drums.

4. A wheel with movable blades comprising two symmetrically arranged drums, adapted to rotate around an axis lying at 20 right angles to the direction of travel of the vehicle, means for simultaneously rotating both drums, slots symmetrically inclined to the axis of rotation of the drums, provided in the periphery of said drums, a transverse 25 stationary crank shaft, collars loosely mounted on said crank shaft in each drum

and independent of said drums, sets of blades pivotally connected to said collars within each of said drums and adapted to pass through the peripheral slots thereof, 35 said blades being driven by the rotation of the drums and being symmetrically inclined to the axis of rotation of the drums in both drums.

5. In a wheel as claimed in claim 1, the provision of means for varying at will the setting position of the crank shaft with relation to the axis of rotation of the drum. 40

6. In a wheel as claimed in claim 2, the provision of means for varying at will the 45 setting position of the crank shaft with relation to the axis of rotation of the drum.

7. In a wheel as claimed in claim 3, the provision of means for varying at will the 50 setting position of the crank shaft with relation to the axis of rotation of the drum.

8. In a wheel as claimed in claim 4, the provision of means for varying at will the setting position of the crank shaft with relation to the axis of rotation of the drum. 55

In testimony whereof I have signed my name to this specification.

FRANÇOIS TRÉCHOT.
